(57) **CLAIM**

I claim the ornamental design for a cell phone holster, as shown and described.

DESCRIPTION

FIG. 1 is a front perspective view of a cell phone holster showing my new design;

FIG. 2 is a front perspective view of a cell phone holster, shown in an open position;

FIG. 3 is a front elevation view of a cell phone holster;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken line showing of a cell phone is included for the purpose of illustrating and forms no part of the claimed design.

The remaining broken lines shown in the drawings represent top-stitching.
